UNITED STATES PATENT OFFICE.

HARRISON D. McFADDIN, OF NEW YORK, N. Y.

DESIGN FOR A LAMP-SHADE.

No. 39,984.

Specification for Design.

Patented May 11, 1909.

Application filed February 23, 1909. Serial No. 479,664. Term of patent 14 years.

To all whom it may concern:

Be it known that I, HARRISON D. McFADDIN, a citizen of the United States, residing at New York, in the county of New York and State of New York, have invented a new, original, and ornamental Design for Lamp-Shades, of which the following is a specification, reference being had to the accompanying drawing, forming part thereof, in which—
Figure 1 is an end view of a lamp shade

showing my new design, Fig. 2 a bottom plan view thereof, and;—Fig. 3 a top plan view thereof.

I claim;—

The ornamental design for a lamp shade as shown.

HARRISON D. McFADDIN.
